Charles G. Hunter,

Chester Bradford,
ATTORNEY.

UNITED STATES PATENT OFFICE.

CHARLES G. HUNTER, OF LAWRENCE, INDIANA.

FINGER-BAR-ADJUSTING DEVICE FOR MOWING-MACHINES.

SPECIFICATION forming part of Letters Patent No. 702,433, dated June 17, 1902.

Application filed February 15, 1900. Serial No. 5,264. (No model.)

To all whom it may concern:

Be it known that I, CHARLES G. HUNTER, a citizen of the United States, residing at Lawrence, in the county of Marion and State of Indiana, have invented certain new and useful Improvements in Finger-Bar-Adjusting Devices for Mowing-Machines, of which the following is a specification.

In mowing-machines as the joints by which the finger-bar is connected to the supporting-framework of the machine wear said finger-bar swings back from its normal position, thus disturbing the alinement between the finger-bar and the direction of motion of the cutter-bar and causing the latter to bind in its movement, so that much friction and wear are occasioned between the parts, which, as is well known, is highly disadvantageous.

The object of my said invention is to provide a means of adjustment for the finger-bar by which the wear above spoken of may be compensated for and the proper alinement between the finger-bar and the direction of motion or path of travel of the cutter-bar be preserved or restored.

A machine embodying said invention will be first fully described and the novel features thereof then pointed out in the claims.

Referring to the accompanying drawings, which are made a part hereof and on which similar reference characters indicate similar parts, Figure 1 is a perspective view of a mowing-machine, otherwise of a well-known form, embodying my present invention; Fig. 2, a top or plan view, on an enlarged scale, of the heel or inner end of the finger-bar and cutter-bar and immediately adjacent parts, that being the point where the mechanism of my invention is located; Fig. 3, a detail top or plan view of the adjusting devices and immediately adjacent parts separately, on a still further enlarged scale, as seen from the dotted line 3 3 in Fig. 4; and Fig. 4, a detail sectional view as seen from the dotted line 4 4 in Fig. 3.

The essential feature of my invention, as will by this time be readily understood, consists in carrying the finger-bar by two points of attachment, one of which is adjustable, so that the position of said finger-bar can be adjusted from time to time by swinging the outer end or point of the finger-bar forward

or back to bring it into proper alinement with the direction of stroke of the cutter-bar carrying the cutter-sections or sickles.

55

In the construction illustrated in the drawings the finger-bar 1 is attached rigidly to the shoe 2 and in which the adjustment is effected between the shoe (which is thus substantially integral with the finger-bar) and the frame 60 part 3 carrying the same. This frame part 3 is bifurcated, and its two branches are pivoted, respectively, to bearing-blocks 4 and 5 by means of ordinary hinge-pivots, as shown. The bearing-block 4 is or may be secured rigidly to the shoe 2 in an ordinary and well-known manner and needs no special description. The base of the bearing-block 5, however, is provided with adjusting-slots and is held to the shoe 2 by means of bolts or rivets 65 70 75 80 secured in said shoe and passing up through said slots, as best shown in Figs. 3 and 4. Attached to or forming a prolongation of the base of the bearing-block 5 is a screw-threaded rod 8, which passes out through a suitable perforation in a lip 9, formed on the shoe 2, and is provided with a nut 10 on its outer end.

The operation is as follows: When the finger-bar becomes disarranged or out of alinement, so that a new adjustment is desired, such adjustment is easily effected by loosening the nuts on the bolts 6 and 7 and adjusting the parts by means of the nut 10 on the screw-rod 8 until the proper relative position 85 is secured, when by tightening down the nuts on the bolts 6 and 7 again the said parts are accurately and firmly secured in adjusted position, and, as is obvious, this may be done repeatedly and as often as becomes necessary 90 or is desired without taking out the cutter-bar or disassembling the machine in any way or interrupting the work for more than a few moments.

Having thus fully described my said invention, what I claim as new, and desire to secure by Letters Patent, is—

1. The combination, in a mowing-machine, of the finger-bar, the shoe, the frame to which it is attached, two attaching-joints one on each side of said finger-bar, one of said attaching-joints being mounted to be adjusted longitudinally in relation to the finger-bar, whereby said finger-bar may be alined with

the direction of the motion of the cutter-bar, substantially as set forth.

2. The combination, in a mowing-machine, of the finger-bar, the shoe, the frame to which
5 the same is attached, bearings on said shoe forming a part of the means of attachment, one of said bearings being slotted and attached to said shoe by means of bolts passing through said slots, a screw-rod projecting from said
10 means of attachment and passing through a suitable eye on said shoe, and a nut on said

screw-rod whereby an adjustment of the finger-bar relative to the parts to which it is attached may be secured, substantially as shown and described.

In witness whereof I have hereunto set my hand and seal, at Indianapolis, Indiana, this 10th day of February, A. D. 1900.

CHARLES G. HUNTER. [L. S.]
